Primary Examiner — Antoine D Davis

(72) Inventor: **Johann Pierre Kok**, Pretoria (ZA)

(74) *Attorney, Agent, or Firm* — Sheridan Ross P.C.

(***) Term: **15 Years**

(57) **CLAIM**

(21) Appl. No.: **29/546,576**

The ornamental design for a signaling and measuring instrument, as shown and described.

(22) Filed: **Nov. 24, 2015**

DESCRIPTION

(51) LOC (10) Cl. **10-04**

FIG. 1 is a perspective view showing my new design; FIG. 2 is a front elevation view of the invention illustrated in FIG. 1;

(52) U.S. Cl.

FIG. 3 is a rear elevation view of the invention illustrated in FIG. 1;

USPC **D10/76**; D10/81; D13/112

FIG. 4 is a left side view of the invention illustrated in FIG. 1;

(58) **Field of Classification Search**

FIG. 5 is a a is a right side view of the invention illustrated in FIG. 1;

USPC D10/75, 76, 81; D13/112

FIG. 6 is a top plan view of the invention illustrated in FIG. 1; and,

CPC G09B 5/12; G09B 19/24

FIG. 7 is a bottom plan view of the invention illustrated in FIG. 1.

See application file for complete search history.
